UNITED STATES PATENT OFFICE.

CARL REICHERT, OF NORTH YAKIMA, WASHINGTON.

SPRAYING APPARATUS.

1,089,083.

Specification of Letters Patent.

Patented Mar. 3, 1914.

Application filed April 17, 1912. Serial No. 691,289.

To all whom it may concern:

Be it known that I, CARL REICHERT, a citizen of the United States, residing at North Yakima, in the county of Yakima and the State of Washington, have invented 5 new and useful Improvements in Spraying Apparatus, of which the following is a specification.

This invention relates to an automatic 10 regulator cut off and safety valve for power spray pumps.

The object of the present invention is to provide an automatic liquid regulator for power spray pumps, which will control the 15 spraying liquid, when the spraying apparatus is in operation and which will also maintain a constant pressure of the spraying liquid, said spraying liquid and pressure being predetermined, means being provided for regulating said spraying liquid 20 and pressure.

A further object of the invention is to provide means for cutting off the supply of liquid to the pump when the nozzle is cut 25 off, allowing the pump to run free, thus reducing wear and saving fuel, the cut off acting as a safety valve for the pump.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed can be made within the scope of what is claimed without departing from the spirit of the invention.

In the drawings—Figure 1 is a sectional view, the valve being open. Fig. 2 is a 40 similar view with the valve closed. Fig. 3 is a perspective view, diagrammatic in character, of a spraying apparatus embodying this invention.

In the drawings, 10 designates the body of 45 the regulator, which forms the cylinder 14 having the inlet 11 which connects to the supply tank 4, and the outlet 12 which connects to the spraying devices.

The contracted portion 15 at the upper 50 end of the cylinder 14, forms the seat for the valve 16 which is a continuation of the piston 17. To prevent any liquid from passing through valve when closed, it is fitted with the leather disk 35, held in place by 55 the washer 34, and nut 33; and for preventing liquid from passing around piston 17,

the leather disk 36 is held in place by the washer 37 and screw 38. The reduced portion 16 of the piston 17 which forms the valve, is to allow for a free passage of the 60 liquid through said valve. Supporting the valve 16 and piston 17 is a rod 18 which passes through the head 19 of the body 10.

A gland 20 containing the packing 29 is 65 adjustably mounted in the head 19 to receive the rod 18. The packing being to prevent any spray liquid from entering the casing 21 to corrode or otherwise injure the spring and other parts.

A casing 21 is supported by the head 19 70 of the body 10, said casing housing the rod 18, spring 30, etc. The sleeve 22 which is the stem of the hand wheel 26, is adjustably supported by screwing into the upper end of the casing 21. The sleeve 22 forming 75 a space for the free working of the rod 18. Attached to the rod 18 by pin 32, or other means so as to move with it, is plate 24, which is the seat for the lower end of the coil spring 30. The upper end of the spring 80 30 rests against the plate 25 which is similar to the plate 24, but loose from the rod 18, and is held in place against the end of the sleeve 22, by the spring 30.

The spring 30 exerts a pressure on the 85 seat 24 attached to the rod 18, thus forcing the piston 17 downwardly in the cylinder 14. The amount of pressure with which the said piston is forced downward, is regulated by turning the hand wheel 26, thus causing 90 more or less compression in the spring.

On the lower end of the body 10 and forming the end of the cylinder 14 is screwed the cap 28 with the threaded pipe connection 27 for connection to the chamber 95 of the spray pump.

The operation of the apparatus is as follows: Normally the tension in the spring 30 holds the piston 17 to the lower end of the cylinder 14, thus leaving the valve open. 100 When the spray pump 6 is started, the liquid is drawn from the supply tank 4 through the opening 11, valve 16 and the opening 12, in the direction indicated by arrows, to the spray pump 6, where it is compressed 105 and forced out into the pump chamber 7, thence to the spray nozzle 9, the said pump chamber 7 being a part of the spray pump 6. Through the pipe leading from the pump chamber 7 and connecting to the part 27 at 110 the lower end of cylinder 14, liquid under the same pressure as in pump chamber 7

is forced into the lower end of cylinder 14, such liquid forcing the piston 17 upwardly into the cylinder 14 against the pressure exerted by the spring 30; thus tending to close the valve 16 and cut down the amount of spray liquid allowed to flow from the supply tank 4 through the valve 16 to the spray pump 6. The greater the pressure of the spray liquid from the pump 6 the nearer closed the valve 16 will be. When the spraying nozzle 9 is cut off, by closing the valve 9^x more liquid is conducted to the lower part of the cylinder 14, due to the immediate slight increase in pressure of the spraying liquid. The incoming liquid contacts with the piston 17 forcing the same upward against the action of spring 30 and closing the valve 16 thus the supply of fluid is immediately cut off when the nozzle 9 is cut off.

Attention is called to the fact that the tension of the spring 30 can be regulated through the medium of the sleeve 22 which is operated by the hand wheel 26, so that any desired pressure may be maintained.

The many advantages of a device of this character will be clearly apparent as it will be noted that the same provides an effective fluid regulation at all times, when the operator of the spray pump 6 is using the spray liquid through the nozzle 9. It is also an effective fluid cut off when the spraying nozzle 9 is cut off and acts as a safety valve for the spray pump 6 at all times. The cutting off of the spray liquid from the pump will also effect a saving of fuel and unnecessary wear on the engine and pump by allowing them to run free. It will also be seen that the structure is such as may be easily and economically manufactured and the various parts readily assembled, and that the device may be applied to spraying

mechanisms now in use without altering their construction.

I claim:

A spraying apparatus including a source of supply of the liquid to be sprayed; a pump provided with a pump-chamber; a valve casing formed with inlet and outlet ports and with a passage therebetween, the inlet port being connected with said source of supply and the outlet port being connected with said pump, whereby the latter is arranged to draw liquid through said passage from said source of supply; a valve mounted in said valve-casing and arranged to control said passage; a spring which normally presses upon said valve and tends to hold the same against closing said passage; means which connect said pump-chamber with said valve-casing on the side of said valve which lies away from said passage and spring, whereby the pressure in said pump-chamber acts to press said valve toward said passage and spring; a spraying device which is connected with said pump-chamber; and means for shutting off communication between said pump-chamber and said spraying device, said valve being arranged to close said passage against the tension of said spring under the influence of the increase of pressure induced in said pump-chamber by shutting off said spraying device and thereby to shut off the supply of liquid from said source thereof, when the spraying device is cut off.

In testimony that I claim the foregoing as my own, I have hereto affixed my signature in the presence of two witnesses.

CARL REICHERT.
